UNITED STATES PATENT OFFICE.

WHITFIELD M. TAGART, OF MALVERN, ARKANSAS, ASSIGNOR OF ONE-HALF TO
SAMUEL R. SULLINBERGER, OF MALVERN, ARKANSAS.

CUTTER-HEAD.

1,149,304.

Specification of Letters Patent.

Patented Aug. 10, 1915.

Application filed August 17, 1914. Serial No. 857,223.

To all whom it may concern:

Be it known that I, WHITFIELD M. TAGART, a citizen of the United States, residing at Malvern, in the county of Hot Springs and State of Arkansas, have invented a new and useful Cutter-Head, of which the following is a specification.

The device forming the subject matter of this application is a cutter head adapted to be used on planing machines for dressing lumber and for cutting moldings and other special shapes.

One object of the present invention is to provide novel means whereby the cutting blades may be held in place without resorting to securing bolts.

Another object of the invention is to provide novel means whereby the blades are supported in their central portions.

Another object of the invention is to provide novel means whereby the blades may be adjusted circumferentially of the cutter.

It is within the scope of the invention to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the accompanying drawing—Figure 1 shows the invention in side elevation, parts being broken away; Fig. 2 is a longitudinal section; Fig. 3 is a cross section on the line 3—3 of Fig. 2; Fig. 4 is a perspective view depicting one of the blades; Fig. 5 is a side elevation showing a modified form of the invention, the blades being omitted.

In carrying out the present invention there is provided a tubular socket or shaft denoted by the numeral 1 and equipped at one end with a head 2 having notches 3 in its periphery. Between the notches 3, the inner edge of the head 2 is under cut as shown at 4 to define overhanging flanges 5. At its opposite end the shaft 1 is threaded as shown at 6. The shaft is provided adjacent the head 2 with a longitudinally extended key seat 7.

Surrounding the shaft 1 and located adjacent the head 2 is an annular cutter support 8 having notches 9 adapted to line up with the notches 3 in the head 2. Intermediate the notches 9, the periphery of the cutter support 8 is fashioned into a plurality of blade supporting tables 10 having transverse teeth or corrugations 11. The cutter support 8 is equipped with a key seat 12 adapted to receive a key 14 lodged in the key seat 7 of the shaft 1.

Surrounding the shaft 1 is a retaining disk 15 having notches 16 in its periphery which line up with the notches 3 and 9 in the head 2 and in the cutter support 8 respectively.

Upon its inner face and adjacent its periphery, the retaining disk 15 is undercut as shown at 17 to define overhanging flanges 18. The retaining disk 15 is supplied with a key seat 19 receiving one end of the key 14.

A plurality of blades 20 are provided, and these blades will be shaped as the work may demand. The blades 20 rest on the tables 10 and are provided with transverse teeth 21 which interfit with the teeth 11 on the tables. At their ends, the blades 20 are beveled as shown at 22, so as to fit beneath the overhanging flanges 5 and 18 of the head 2 and the retaining disk 15 respectively. The cutting edges of the blades are indicated at 23 and may be shaped as desired.

Threaded onto the portion 6 of the shaft 1 is a nut or collar 24 adapted to bear against and to exert a pressure on the retaining disk 15.

In order to remove or adjust the blades 20, it is necessary to back the nut or collar 24 away from the retaining disk 15 so as to release the hold of the head 2 and the retaining disk on the edges of the blades. The blades then may be removed or may be adjusted circumferentially of the cutter support 8, upon the tables 11, the interfitting corrugations or teeth 21—11 serving to hold the blades in position after adjustment.

It is to be observed that the collar or nut 24 constitutes an efficient means for moving the disk 15 toward the head 2, to bind and retain the blades, through-bolts and other equivalent structures being dispensed with.

The blades 20 not only are supported along their edges, but, referring to Fig. 2, it will be observed that the element 8 supports the blades between the disk 15 and the head 2.

Referring to Fig. 5, the shaft is shown at 25, the head at 26, the supports at 27, the retaining disk at 30 and the nut at 31. Between the supports 27 is interposed a spacing disk 28 which is under cut at 29 at its periphery and upon both sides to receive the edges of the blades, the structure shown in Fig. 5 being employed when more than one set of cutters is used. The spacing disk 28 5 may be considered as a retaining head so far as are concerned those blades which lie between the spacing disk 28 and the retaining disk 30. Therefore, in both forms of the invention there is disclosed a shaft having a 10 head, a retaining disk on the shaft, a blade bound between the head and the retaining disk, and a nut threaded on the shaft and exerting a pressure against the retaining disk.

Having thus described the invention, what is claimed is:

1. In a device of the class described, a shaft having a head; a retaining disk on the shaft and adjustable toward and away from the head; an annular cutter support on the shaft between the head and the disk; and a blade resting on the support, the blade and the support having interfitting teeth extended longitudinally of the shaft and serving to hold the blade in adjusted positions against movement circumferentially of the shaft, the disk and the head upon the one hand and the blade upon the other hand being provided with mutually interengaging faces inclined longitudinally of the shaft and coacting to move the blade toward the center of the shaft thereby to hold the teeth of the blade and the support interengaged when the disk is moved toward the head, the disk being movable away from the head thereby to permit the teeth of the blade and of the support to be disengaged and to permit the blade to be adjusted circumferentially of the shaft.

2. In a device of the class described, a shaft having a head; a disk mounted on the head for adjustment toward and away from the head; a support located on the shaft between the disk and the head and movable toward and away from the head; a blade upheld by the support and clamped between the disk and the head; the blade, the support and the disk having peripheral notches, and the notch in the support lying beneath the working edge of the blade; and a shaft 50 carried key engaging the support and the disk to hold the same against rotation there-

by to aline all of the notches and to cause the same to form a continuous, chip-discharging channel.

60

3. In a device of the class described, a shaft having a head, the shaft being threaded at a point remote from the head and being provided with a key seat located between the threaded portion of the shaft and the head; a removable key in the seat and held against endwise movement therein; a disk on the shaft and having a seat receiving the key; a nut on the threaded portion of the shaft and engaging the disk, one end of the key being spaced from the nut; a support on the shaft between the head and the disk and having a key receiving seat; and a blade upheld by the support and clamped between the disk and the head.

75

4. In a device of the class described, a shaft having a head; a disk mounted on the shaft for adjustment toward and away from the head; a support located on the shaft between the disk and the head and movable toward and away from the head; a blade upheld by the support; the blade, the support and the disk having peripheral notches and the notch in the support lying beneath the working edge of the blade; a shaft carried key engaging the support and the disk to hold the same against rotation, thereby to aline all of the notches and to cause the same to form a continuous chip discharging channel; the blade and the support having interfitting teeth extended longitudinally of the shaft and serving to hold the blade in adjusted positions against movement circumferentially of the shaft, the disk and the head upon the one hand and the blade upon the other hand being provided with mutually engaged faces inclined longitudinally of the shaft and coacting to move the blade toward the center of the shaft thereby to hold the teeth of the blade and the support interengaged when the disk is moved toward the head, the disk being movable away from the head thereby to permit the teeth of the blade and of the support to be disengaged and to permit the blade to be adjusted circumferentially of the shaft.
